UNITED STATES PATENT OFFICE.

RALPH L. INGEBRIGTSEN, OF MISSOULA, MONTANA.

RULING-PEN ATTACHMENT.

1,262,801.

Specification of Letters Patent. Patented Apr. 16, 1918.

Application filed March 12, 1917. Serial No. 154,259.

To all whom it may concern:

Be it known that I, RALPH L. INGEBRIGTSEN, a citizen of the United States, residing at Missoula, in the county of Missoula, State 5 of Montana, have invented certain new and useful Improvements in Ruling-Pen Attachments; and I do hereby declare the following to be a full, clear, and exact description of the invention, such as will enable others 10 skilled in the art to which it appertains to make and use the same.

This invention relates to improvements in draftsmen's ruling pens, and particularly to attachments therefor.

15 One object of the present invention is to provide a novel and simple device for accurately gaging the width of the line the pen is to make.

Another object is to provide a device of 20 this character which can be quickly and easily slipped onto the ordinary ruling pen now in use.

A further object is to provide a device of 25 this character whereby the draftsman can instantly tell to what degree he is opening or closing the jaws of the pen, when he turns the adjusting screw in either direction.

Other objects and advantages will be apparent from the following description when 30 taken in connection with the accompanying drawing.

In the drawing:

Figure 1 is a front elevation of a ruling pen equipped with my gage attachment.

35 Fig. 2 is a side elevation of the same.

Fig. 3 is an enlarged longitudinal sectional view taken on the line 3—3 of Fig. 1.

Fig. 4 is an enlarged transverse sectional view taken on the line 4—4 of Fig. 1.

40 Referring particularly to the accompanying drawing, 10 represents the rigid or stationary leg or jaw of the ruling pen, and 11 the adjustable and flexible leg or jaw. The adjusting screw 12 is disposed loosely in the 45 opening 13 in the jaw 11, and threaded into an opening 14 in the jaw 10. The upper portion of the jaw 11 is reduced in thickness or flattened to produce the required amount of flexibility in the jaw. The head of the 50 screw is formed with the milling 15 around the peripheral edge, as clearly shown in the drawing. In connection with the said reduced portion of the jaw 11 and the milled head of the screw my invention is used.

55 The attachment includes a base member 16 having an integral pair of outwardly

bowed legs 17 which have their extremities directed inwardly toward each other, at 16', and arranged to grip the opposite edges of the flattened portion of the leg or jaw 11, 60 when the screw is removed. Formed integrally with the base, and extending longitudinally thereof, is a cylindrical member 18, both ends and the intermediate portion of one side of which are open, as clearly shown 65 in the sectional view Fig. 4. Within the cylindrical member there is secured a tubular member 18', and in the outer portion of the lower end of the tubular member there is formed a bayonet slot 19. Slidably disposed in the lower end of the member 18' is a pin 20, the projecting end of which is formed with a double chisel point 21, engaging with the milling of the head of the screw. In the other end of the member 18' 70 there is secured a transverse pin 22, and within the member 18', and engaging against the pin 22, and against the inner end of the pin 20, is a coil spring 23, the tendency of which is to normally urge the pin 20 out of 75 the member 18'. Carried by the pin 20, and playing in the bayonet slot, is a headed finger-piece 24. By grasping this finger piece the pin 20 can be withdrawn into the tubular member whereby said pin can be held out 80 of engagement with the screw head.

It will thus be seen that the double chisel point of the pin 20 will ratchet over the milling of the screw head as the screw is turned, and by the feel of this engagement, 90 by the fingers of the draftsman, as he turns the screw, the distance the screw has been turned in either direction, can be accurately told. Thus, when the screw is turned two notches of the milling in one direction, the 95 draftsman knows how much wider or thicker the line will be, than before the screw was turned. This is especially of value in making shade lines, where the lines are successively made thicker or thinner, according 100 to the direction of movement of the angle or square.

The device is extremely simple in construction, and can be quickly and easily applied to the ordinary pen, or removed therefrom, by simply removing the adjusting screw of the pen. 105

By reason of the fact that the legs 17 are resilient, the device will be firmly but releasably engaged on the leg or jaw 11 of the 110 pen. It may not be necessary to remove the adjusting screw 12 when applying the de-

vice, as the legs may be readily sprung apart so as to be engaged with the jaw 11.

What is claimed is:

An attachment for a ruling pen including
5 a base member having resilient legs provided
with inturned extremities adapted for em-
bracing engagement with one jaw of the
pen, the pen being provided with a milled
headed screw, a tubular member carried in
10 the base and having a bayonet slot in the
side at one end thereof, a coil spring dis-
posed in the tubular member, a double chisel

pointed pin slidable in the tubular member
and engaging with the milled head of the
screw, means for holding the spring in en-
gagement with the pin, and a fingerpiece
carried by the pin and slidable in the said
bayonet slot. 15

In testimony whereof, I affix my signature,
in the presence of two witnesses.

RALPH L. INGEBRIGTSEN.
